3,054,410 FILTER CIGAR

Lewis N. Gould, 2058 Cropsey Ave., Brooklyn, N.Y.
Filed Oct. 19, 1960, Ser. No. 63,575
2 Claims. (Cl. 131—10)

This invention concerns a cigar with a filter tip.

According to the invention there is provided a cigar to the mouth end of which is applied a filter tip. The tip is formed as a tubular member secured to the cigar. Within the tubular member is a cylindrical body of porous material which serves as a filter to extract nicotine, tars and solid particles from the tobacco smoke passing therethrough. The filter tip renders the cigar cleaner and more comfortable to hold in the mouth than a bare cigar tip. The filter tip absorbs tobacco juices, prevents disintegration of the mouth end of the cigar and permits the cigar to be smoked more completely. The porous filter material may be made of various vegetable or synthetic fibers, Fiberglas, rock wool, cellulose, charcoal activated powdered material such as kaolin, or the like.

It is therefore one object of the invention to provide a cigar with an improved filter tip.

It is a further object to provide a filter tip for a cigar.

It is another object to provide a flexible tubular attachment for a cigar, said attachment containing a body of porous filter material.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a perspective view of a cigar embodying the invention.

FIG. 2 is a longitudinal sectional view taken on line 2—2 of FIG. 1.

FIG. 3 is a sectional view similar to a portion of FIG. 1 showing a further embodiment of the invention.

FIG. 4 is a perspective view of a portion of another cigar embodying another modification of the invention.

FIG. 5 is a longitudinal sectional view taken on line 5—5 of FIG. 4.

FIG. 6 is a perspective view of the portion of the cigar of FIGS. 4 and 5 showing the form assumed thereby during use.

FIG. 7 is a view similar to FIG. 4 of another modification of the invention.

FIG. 8 is a sectional view taken on line 8—8 of FIG. 7.

FIG. 9 is a perspective view of a filter tip alone according to the invention.

Referring to FIGS. 1 and 2, there is shown a cigar 10 having a generally cylindrical body 12 formed of tobacco leaves rolled in conventional fashion. At the mouth end 14 of the cigar is secured a flexible tubular jacket 16 formed of non-porous, moisture-proof plastic or paper material. The jacket may be secured to the mouth end of the cigar by a suitable adhesive 18. Within the tubular jacket is a cylindrical body 20 of porous filter material. This body may be enclosed in a tubular paper wrapper 22.

The filter tip T including jacket 16 and the porous body 20 may be assembled prior to mounting on the mouth end of the cigar body. The portion of the jacket extending beyond the body 20 defines a recess 21 which fits snugly on the mouth end of the cigar.

In FIG. 3 the filter tip T' includes a tubular paper jacket 16^a coated or covered by a non-porous layer 17 of synthetic resin or plastic material such as polyethylene, vinyl

2

or the like. Adhesive 18 secures the tip T' to the cigar body 12^a.

In FIGS. 4 and 5 the filter tip T'' has a pliable jacket 16^b formed with a closed end 25 in which are a plurality of parallel spaced slits 26. The closed end of the jacket keeps the porous filter body 20 more securely within the jacket prior to and during smoking of the cigar. When the cigar is to be smoked, the smoker initially closes his teeth on the jacket which compresses it at its end 27 to flattened or oval form as shown in FIG. 6. This causes the slits 26 to spread and form openings 26' through which the smoke passes while the cigar is being smoked. The filter tip retains its flattened or oval form while being smoked primarily due to the pliable nature of the jacket. 15 The jacket may be made of metal foil, or a non-porous plastic material which is pliable and shape-retaining when pressed. The jacket overlays the paper layer wrapper 22. If desired, this wrapper may be omitted and the porous body 20 may be packed in the jacket alone. Adhesive 18 secures the jacket to the mouth end 14 of the cigar body 12^b.

In FIGS. 7 and 8 the structure of the jacket 16^c is like jacket 16^b with closed end 25 and slits 26. Adhesive is omitted and the inner end of the jacket is formed with 25 annular ribs or corrugations 23 which effectively secure the filter tip F to the mouth end of the cigar body 12^c. Jacket 16^c is made of metal foil.

In all the embodiments of the invention, the filter tip is flexible so that it can be comfortably held between the lips or teeth of the smoker. The porous body 20 is preferably non-combustible and may be made of fibers of Fiberglas or rock wool. However, organic materials such as cellulose fiber may be used. Granulated or compressed powdered materials may also be employed. In any case the filter material should have good moisture absorbency and should be chemically inert to avoid giving off fumes when the smoke passes through.

The provision of filter tips as described makes cigar smoking more enjoyable, cleaner and more satisfying. 35 The filter tips can be fabricated and applied by conventional, high speed mass production at low cost.

If desired, the filter tips can be fabricated as separate units as shown by tip F' in FIG. 9, and sold separately for assembly on a conventional cigar made without filter tip. The smoker can apply the filter tip by moistening the mouth end of the cigar and pushing on the mouth end of the cigar into the recess 21 in jacket 16^d where the adhesive will become moistened to secure the filter tip of the cigar.

50 Another improvement of the invention may be made with a pre-formed filter in which the filter itself may be tobacco with pre-treated filtering material or powder which may be dipped into plastic or latex liquid to cover the same and to form a protected cigar mouth tip.

55 While I have illustrated and described the preferred embodiments of my invention, it is to be understood that I do not limit myself to the precise constructions herein disclosed and that various changes and modifications may be made within the scope of the invention as defined in the appended claims.

Having thus described my invention, What I claim as new, and desire to secure by United States Letters Patent is:

65 1. A cigar comprising an elongated generally cylindrical body of rolled tobacco leaves having a mouth end of reduced diameter, a flexible tubular moisture-proof jacket having one end secured to said mouth end by an adhesive and extending outwardly axially from said mouth end, and a porous filter enclosed in a paper wrapper fitted in said jacket for filtering smoke passing therethrough, said jacket having a closed end formed with a plurality of transverse

normally closed slits, said packet being pliable so that the slits are adapted to open upon compression of the jacket.

2. As an article of manufacture, a filter tip for a cigar comprising a tubular body of flexible moisture-proof material, a cylindrical body of porous material enclosed in said tubular body and terminating short of one end to define a recess adapted to receive the mouth end of the cigar, and a layer of adhesive lining the tubular body at said one end for securing the filter tip to the cigar, the other end of said tubular body being closed and having transverse slits normally closed therein, said tubular body being pliable so that the slits are adapted to open upon compression of the jacket. 5 10
